UNITED STATES PATENT OFFICE.

JOHN A. BUTKUS AND HERMAN T. GAY, OF BALTIMORE, MARYLAND; ADOLPH FREDERICK SCHOEN AND JOHN W. DARLEY ADMINISTRATORS OF SAID JOHN A. BUTKUS, DECEASED; SAID ADMINISTRATORS AND SAID GAY ASSIGNS OF TWO-FIFTHS TO ADOLPH FREDERICK SCHOEN AND JOHN W. DARLEY AS ADMINISTRATORS, ONE-FIFTH TO SAID GAY, SEVEN-TWENTIETHS TO ARTHUR KREATSCHMANN, OF MORNELL PARK, MARYLAND, AND ONE-TWENTIETH TO WALTER J. WISCH, OF BALTIMORE, MARYLAND.

CAR-COUPING.

1,289,646.

Specification of Letters Patent. Patented Dec. 31, 1918.

Application filed June 16, 1917. Serial No. 175,100.

To all whom it may concern:

Be it known that we, JOHN A. BUTKUS and HERMAN T. GAY, the said JOHN A. BUTKUS being a citizen of the United States and the said HERMAN T. GAY a subject of the Emperor of Germany, residing at Baltimore, in the State of Maryland, have invented new and useful Improvements in Car-Couplings, of which the following is a specification.

10 This invention relates to certain improvements in that class of car couplers in which are employed hooked jaws which move in a horizontal direction and interlock in the coupling operation, as will hereinafter fully 15 appear.

In the description of the said invention which follows, reference is made to the accompanying drawings forming a part hereof, and in which—

20 Figure 1 is an exterior side view of the adjacent ends of two cars coupled together by means of our improved coupler. Fig. 2 is an enlarged top view of the couplers alone, showing them as interlocked. Fig. 3 is an 25 exterior side view of Fig. 2. Fig. 4 is a view similar to Fig. 2 except that the couplers are shown therein as not connected. Fig. 5 is a sectional plan of one of the couplers with the various parts thereof occupying the 30 same relative position illustrated in Fig. 4. Fig. 6 is a section of Fig. 5 taken on the dotted lines $\alpha-\alpha$. Fig. 7 is a view similar to Fig. 5 except that the various parts thereof are shown as occupying the same relative 35 positions illustrated in Fig. 2. Fig. 8 is a section of Fig. 7 taken on the dotted line $\nu-\nu$. Fig. 9 is an end view of Fig. 7 looking in the direction indicated by the arrow. Fig. 10 is an enlarged view, in section, of certain parts shown in Fig. 7. Fig. 40 11 illustrates a modification in the construction of certain parts of the coupler, as hereinafter described.

Referring now to Figs. 1 to 10, inclusive, 45 of the drawings, A and B, shown only in Fig. 1, are the adjacent platforms of two cars. It will be understood that the couplers

of the two cars are identical in construction, and consequently the description of one of them will apply to the other.

50 C is the draw head having the hollow extension a which serves as the draw bar.

The draw head is hollow, and the outline of its extremity as seen from either the top or bottom, is concave or inwardly curved. 55 One side of the curved extension of the draw head projects considerably beyond the other, thereby producing the horn D, the purpose of which will hereinafter appear. Portions of the draw head are provided with strength- 60 ening beads or flanges b.

E is a hooked jaw mainly connected to the head C by the pin or lock F which passes through the upper plate c of the head which is provided with a boss d to strengthen it, 65 and is adapted to enter a hole e in the boss f on the lower side of the under plate g of the head.

The hook proper h of the jaw is considerably thicker than the main portion within 70 the head and the latter is provided with a hole j through which the lock F passes when the couplers are interlocked.

Extending back from the hole j is a curved 75 channel k the surface l of which is lower at its rear end than at the portion adjoining the hole, as shown in Figs. 6 and 8. The lock F, when the cars are uncoupled, rests on the lowest part of this inclined surface, and some resistance is offered to the closing 80 of the hooked jaw for the reason that in that operation the lock F is elevated. In other words, this construction of the hooked jaw prevents accidental swinging-in of the jaw.

G is a second pin whereby the hooked jaw 85 E is pivoted within the draw head C. It is provided with an enlargement or ball n at its upper end to prevent its passing entirely through the draw head. The hole for this pin in the hooked jaw is round, but the holes 90 p in the upper and lower plates c and g , respectively, consist of curved slots, and consequently the pivotal point is variable to the extent of the length of the slots. The

object of this peculiar construction will be hereinafter described.

The hooked jaw E has a curved and flared tail-piece q against which the hook of the hooked jaw of the adjoining coupler strikes and which effects the swinging-in of the jaw in the coupling operation. The swinging-in of the jaw is also effected by the horn b of the other coupler against which it strikes, and in practice one of these expedients assists and coöperates with the other as the couplers come together.

While the pivotal point of the hooked jaw is susceptible of change in position as described, it is normally fixed by means of the bar H one end of which is pivoted to the jaw at s. The other end of the bar passes through a hole t in a plate I loosely inserted in the hollow draw bar a and bears against projections u. These projections are shown on an enlarged scale in Fig. 10.

The end of the bar has a knob which prevents its withdrawal from the hole t, and coiled about the said bar and confined endwise between the plate I and the lug v to which the bar is connected, is a suitable spring J.

The spring J is stiff enough to keep the pin n in ordinary circumstances, against the right hand end of the slot p, or more properly speaking, the pin and draw head in the relative positions shown in Figs. 2, 4, 5 and 7 of the drawings. This being the case, when the hooked jaw is struck suddenly by the tail piece of the corresponding coupler of the other car, or by a link, should it be necessary to couple with such device, it will yield slightly and thereby prevent injury to the hook and its connections.

The employment of the yielding pivot also admits of a limited outward movement of the locked hooks when the cars are rounding a curve, reducing a rigidity which might tend to place additional strain on the hooks at such time.

To admit of the connection of the hooked jaw with an ordinary coupling link, which in some cases may be necessary, the hook is provided with a slot K, and a hole w for an ordinary coupling pin.

Any suitable mechanism may be employed to lift the lock F without going between the cars, but that which we prefer consists of a lever L pivoted at a² to a bracket b¹ projecting from the top of the draw head and pivoted to the pin, a chain M and a bell crank lever N journaled at c² to the platform of the car.

An alternate construction is shown in Fig. 11 in which the lock F has a downward extension d² which passes through a slot e² in the inclined bottom j of the channel k, and a lever O having its fulcrum f¹ underneath the head.

Supposing the elements of the couplers to be in the relative positions shown in Fig. 4 with the locking pins resting on the inclined bottoms of the channels k; as the cars are brought together, each hooked jaw is thrown in, either by its being struck by the tail piece of the opposite jaw, or by coming in contact with the inclined surface of the opposite horn, and as the locking pin is now directly over the hole e it drops, and the coupling operation is completed.

The uncoupling is effected by merely raising the locking pins, the hooked jaws opening outwardly in the separation of the cars. When the locking pins are again allowed to drop, they will rest on the inclined bottoms of the channels k which hold them in an elevated position until the coupling operation described has to be repeated.

Having thus described our invention, we claim:—

1. In a car coupler, a pivoted hooked jaw having a lock hole and a surface leading from the same which is lower than the upper surface of the jaw, the said surface being downwardly inclined as it recedes from said hole, substantially as specified.

2. In a car coupler, the combination of a draw head having a hollow draw bar extending therefrom containing a plate, a hooked jaw having a variable pivotal point, a bar pivoted to the said hooked jaw extending through a hole in the plate in the hollow draw bar with a knob at its end, and a spring coiled about the said bar and confined endwise between the plate and the hooked jaw, substantially as specified.

3. In a car coupler, a hollow draw head having a vertically extending lock hole, and the upper and lower plates thereof provided each with a curved slot, the said slots being arranged one over the other and practically concentric with the lock hole, combined with a loose lock, a hooked jaw having a hole for the said lock, with a bottomed channel leading therefrom, substantially as described, a pivotal pin secured in the said jaw with its ends which project above and below the said jaw, inserted in the said curved slots, and spring mechanism to yieldingly hold the said pivotal pin at one end of the said curved slots, substantially as and for the purpose specified.

4. In a car coupler, a hollow draw head having the upper and lower plates thereof provided each with a lock hole, the said holes being in alignment, and also with a curved slot, the said slots also being in alignment one with the other, combined with a vertically moving locking pin in alignment with said lock holes, and a hooked jaw having a lock hole and a bottomed channel leading therefrom, substantially as described, and provided with a secured pin having its

ends projecting above and below the jaw, the said projecting ends resting in the said slots in the upper and lower plates of the draw head, and spring mechanism to yieldingly hold the said pivotal pin at one end of the said slots, substantially as and for the purpose described.

Copies of this patent may be obtained for five cents each, by addressing the "Commissioner of Patents, Washington, D. C."

In testimony whereof we affix our signatures in presence of two witnesses.
